UNITED STATES PATENT OFFICE.

FRANK L. CONE, OF WINDSOR, VERMONT, ASSIGNOR, BY MESNE ASSIGNMENTS, TO THE NATIONAL-ACME COMPANY, OF CLEVELAND, OHIO, A CORPORATION OF OHIO.

METAL-WORKING MACHINE.

1,215,000.

Specification of Letters Patent.

Patented Feb. 6, 1917.

Application filed November 23, 1915. Serial No. 62,967.

To all whom it may concern:

Be it known that I, FRANK L. CONE, a citizen of the United States, residing at Windsor, in the county of Windsor and State of Vermont, have invented new and useful Improvements in Metal-Working Machines, of which the following is a specification.

This invention has relation to metal-working machines, and particularly to those in which a plurality of tools are presented successively by a turret to the work for operating thereon. The object of the invention is to provide a mechanism adapted to be supported on the turret for performing the operation known as "forming", and thereby to produce the finished work rapidly and with accuracy. To this end the turret is provided with a cross slide equipped with a cutter of the desired character, which is brought automatically into potential working position, after which by automatic mechanism the cross slide is moved transversely with reference to the work axis to cause the cutter to perform its operation.

On the accompanying drawings, which illustrate one embodiment of the invention:

Figure 1 represents, in side elevation, a single-spindle turret machine equipped with mechanism embodying the invention.

Fig. 2 represents an end elevation of the same, looking toward the end of the turret.

Fig. 3 represents a similar end view, partly in section, on the line 3—3 of Fig. 1, and a portion of the case being removed to show the construction of one of the operating cams.

Fig. 4 represents a rear elevation of the turret and adjacent parts.

Fig. 5 represents a vertical transverse section through the machine, the work spindle being shown in section.

Fig. 6 represents, in part, a similar section with the cross slide just completing its outward movement.

Fig. 7 illustrates, on a larger scale, a plan view of the turret end of the machine.

Fig. 8 represents a longitudinal vertical section through the turret and adjacent parts.

Figs. 9 and 10 illustrate, in detail, the construction of the cross slide, showing the latter in two different positions.

Fig. 11 illustrates, on a larger scale, in plan view, the cross slide and adjacent parts.

On the drawing I have shown my invention as being constructed for operation upon what is known as the "Gridley single-spindle machine", the details of construction of which it will be unnecessary herein to describe. It will be understood, however, that the invention is not necessarily limited to this particular type of turret machine, as it may be utilized on machines of other types. I desire to have it understood, before proceeding to a detailed description of the machine, that the parts are shown more or less conventionally and that the phraseology which I herein employ is for the purpose of description and not of limitation.

Referring to the drawings,—the frame of the machine is indicated as a whole at 20, and it is provided with bearings for the spindle which is indicated at 21. Suitable mechanism is utilized for rotating the spindle at the desired speeds, and also for automatically feeding the stock from which the work is to be produced therethrough. These features, however, are not intimately connected with the subject-matter of the present invention and need not be described.

The frame of the machine, as shown in Fig. 8 is provided with a bearing 22 in which is journaled one end of the turret 23. This turret is provided with a plurality of tool slides, one of which is indicated at 24 and the others of which are indicated at 25. The turret is hollow as shown, and each slide is provided with a pin or projection 26 extending into the interior thereof. Any suitable mechanism, which need not be described in detail, is utilized for indexing the turret so as to bring the slides successively into position to present the tools thereon to the work which is held in the spindle. For feeding the tool slides successively lengthwise of the turret and axially of the work spindle, there is a reciprocating bar 27 having thereon a block 28 provided with a groove into which the several pins 26 are 100

5 moved in succession as the turret is rotated with a step-by-step movement. It is unnecessary to describe the mechanism for reciprocating the bar 27, as it is illustrated and described in detail in Letters Patent to George Otis Gridley, 725,438, dated April 14, 1903.

10 It will be understood that the turret is rotated with a step-by-step movement at intervals and that, after it has completed each step and is locked in position, the tool slide then in potential working position is advanced and retracted longitudinally of the work. The tool slide 24 is 15 formed on its face with a guideway consisting of a dovetail groove 29 on which there is mounted a cross slide 30. On said cross slide may be mounted any suitable form of tool, but I prefer to mount thereon 20 a forming cutter 31 which will perform what is known as a "finishing cut". This cutter may be secured in place in any suitable way, and I have shown the slide as provided with a bridge bar 32 through which clamping 25 screws 33 may be passed downwardly to clamp the cutter 31 tightly upon the cross slide. The character and shape of the cutter 31 will depend upon the form of the finished work. For example, it may be so 30 formed as to provide the finished cut on the hub of a motorcycle wheel or upon any other piece of work which is round in cross section.

35 The bridge bar 32 is provided with an upward extension 34 at one end thereof and is provided with a clamp 35 and a socket for the reception of a cutting-off tool 36. After the main tool slide 24 has been moved axially toward the work, the cross slide 40 is moved transversely to cause the cutters supported thereby to perform their operations upon the work, after which the cross slide is withdrawn and the main slide 24 is moved outwardly away from the spindle to 45 inactive position.

50 Any suitable mechanism may be utilized for operating the cross slide. In the present instance I employ an arm 37 such as is utilized in the Gridley machine for feeding one of the supplemental tool holders mounted on the bed. In the present case the two-armed lever 37 is fulcrumed upon the bar 38 which is supported by the bed, and its depending arm is provided with a 55 roll 39 to be engaged by suitable cams 40 mounted upon the inner face of a cam disk 41 located upon the cam shaft 42. This shaft 42 is the main cam shaft of the machine and is driven by any suitable mechanism, which need not be described but which is explained in detail in the Gridley patent previously referred to. In my application for patent, Serial No. 6,879, filed February 8, 1915, I have described a suitable

65 ble mechanism which may be utilized for driving this shaft 42 at different speeds, either with the spindle or independently thereof.

70 On the end of the upper arm of the lever 37 there is a guideway 43 (see Fig. 4) for the reception of an adjustable extension 44 of the said arm. Any suitable means may be utilized for securing the said extension after adjustment. The extension is provided with a roll 45 which enters and engages a groove 46 formed in the side of the cross slide 30, the roll and the walls of the groove constituting complementary 75 interlocking members for interlocking the lever and the cross slide. When the main slide 24 is moved toward the spindle, the cross slide engages the roll 45, and thereafter when the lever 37 is rocked it moves the cross slide with it, as will be readily understood.

80 It is desirable that the cross slide shall be locked in position when it is not being operated. It will be noted, in Fig. 6 for example, that the cross slide projects laterally beyond the main slide 24, and that it is 85 provided with a depending block 47 having a groove 48. To the turret is secured a locking bar 49 having a rib 50 which registers with the groove 48 and which is caused to enter the groove when the main slide 24 reaches the end of its travel away from the work spindle. After the main slide has been moved a short distance toward the spindle, the rib 50 becomes disengaged from the block 47 and permits the cross slide to be 90 fed transversely. When the main slide 24 is 95 out of potential working position the cross slide is securely locked against movement relatively thereto.

100 I have stated that the cross slide carries the forming cutter which performs the finishing operation. The roughing former is preferably mounted upon a supplemental tool slide 51 mounted upon the bed and upon transverse ways afforded thereby, as indicated at 52 in Fig. 1. The roughing cutter is indicated at 53 and is clamped by any suitable means in a tool holder 54 secured to the supplemental tool slide 51. Said tool slide and its operating mechanism do not 105 differ materially from the equivalent parts shown in my application to which I have herein previously referred. In the present instance the tool slide 51 is reciprocated by a two-armed lever 55 journaled on a stud 56, shown in Fig. 3. The upper end of the arm is provided with an adjustable pin 57 bearing against the depending block 58 of the tool slide. The said lever is also provided with a roll 59 for engagement with the bracket or lug 60 secured to the tool slide. The lower end of the lower arm is provided 110 with a roll for engagement by the cams 61,

62 on the cam disk 41 to which reference has previously been made. As a matter of detailed construction it will be noted that the cutter 53 rests upon an adjustable wedge 5 63 so that it may be adjusted both as to height and lateral position relatively to the work.

One of the features of the present invention consists in a device mounted upon the 10 slide 24 in the rear of the cross slide for holding the work against cutting strains and thereby preventing "chattering" and the formation of a rough surface. Where the end of the bar upon which operations are 15 being performed is hollowed out as by means of a boring tool and a reamer, I provide a work support which enters the cavity in the work. Where the finished work is solid, on the other hand, I may provide a 20 work rest which will engage the periphery thereof at its outer end. As shown, however, the slide 24 is provided with a holder 25 70. This is secured by any suitable means upon the top of the slide 24 and may be of any suitable construction. As shown, in Fig. 9 for example, it is split at one side to form two clamping members one of which is drawn toward the other by a screw 71. In this clamping holder is inserted a bar 72 30 which, when the slide 24 is in potential working position, is in axial alinement with the work spindle. The end of the bar 72 which projects toward the spindle is reduced and is provided on its reduced end with a 35 roll 73 of a size sufficient to fit nicely within the cavity in the work. This roll is held in place by a washer 74 and a screw 75.

The operation of the mechanism will be 40 readily understood from the foregoing description. Assuming for instance that the work to be produced is the hub of a motorcycle wheel and that the preliminary operations of boring and reaming have been completed, the next rotative movement of the 45 turret brings the slide 24 into potential working position. Thereupon by means of the bar 27 the slide 24 is advanced rapidly toward the spindle, carrying with it the cross slide 30. As the slide 24 moves forwardly, the block 47 is disengaged from the lock 49 so that the cross slide is free to be moved transversely of the work. As the 50 slide 24 continues its movement toward the bed it finally reaches a position in which the 55 roll 73 of the work support or work rest has entered the open end of the hollow piece of work and the roll 45 on the lever 37 has entered or become engaged with the groove in the end of the cross slide. Thereupon the 60 slide 24 is held at rest. Then the supplemental tool slide 51 is operated to move it toward the work so that the cutter thereon, which is of the proper shape and character, performs what is known as the rough-

ing forming cut. After the roughing cutter has completed its operation, the finishing cutter on the cross slide engages the work and completes the cut. The movement of the cross slide, however, continues until the cutting-off cutter has completely severed 65 the finished piece of work, after which the cross slide is returned to its initial position and the slide 24 is fed backwardly away from the work spindle to its original starting point. Thereupon the turret is indexed. 70 The two cutters, that is, the roughing cutter and the finishing cutter, may both operate simultaneously upon the work, and the cutting-off cutter may start its cut before the forming is completed. 80

From the foregoing description it will be apparent that the operation of the tool slide 24 and the operation of the cross slide 30 are controlled from the same feed or drum shaft 27 through suitable cams mounted 85 thereon.

The mechanism which I have herein described as embodying some of the features of the invention, to wit, the main slide 24 having a cross slide thereon, the work rest, 90 and cutters supported by the cross slide, may all be sold separately as an attachment for the Gridley machine, or they may be incorporated directly in the machine in the course of its manufacture. 95

Having thus explained the nature of my said invention and described a way of constructing and using the same, although without attempting to set forth all the forms in which it may be made or all the modes of 100 its use, what I claim is:

1. A metal-working machine comprising a work spindle, a cam, a lever actuated thereby, a tool slide movable longitudinally of the work spindle, a cross slide on said main 105 tool slide, and separable means for interlocking said cross slide with said lever.

2. A metal-working machine comprising a work spindle, a main tool slide, means for revolving said main tool slide to move it 110 into and out of potential working position, a cross slide on said main tool slide, a member for actuating said cross slide, said cross slide and said member having complementary 115 separable interlocking elements, and means for moving said main slide to cause said cross slide to interlock with said actuating member.

3. A metal-working machine comprising a work spindle, a turret movable about an axis 120 parallel with that of the work spindle, a main tool slide thereon, a cross slide mounted on said main slide, means for holding said cross slide from movement when the main slide is withdrawn, means for moving said main tool slide on said turret toward and from the work spindle, a cam, and a lever actuated thereby for automatically op-

4
erating said cross slide when it is in a forward position adjacent the spindle.

4. A metal-working machine comprising a main frame, a work spindle journaled therein, a turret movable about an axis parallel with that of the work spindle, a cross slide thereon, mechanism for effecting a relative movement of said cross slide and said spindle in a direction lengthwise of said spindle, a rotary cam supported on said bed, and a cam-operated lever supported on said bed for moving said cross slide transversely with relation to said work spindle.

5. A metal-working machine comprising a main frame, a work spindle journaled therein, a turret movable about an axis parallel with the work spindle, a cross slide thereon, mechanism for moving said cross slide bodily lengthwise of said work spindle, a lever supported by said bed, mechanism for automatically rocking said lever, and complementary interlocking members on said lever and said cross slide adapted to be alternately engaged and disengaged by the movement of the cross slide toward and from the work spindle.

6. A metal-working machine comprising a work spindle, a turret, a main tool slide thereon, a cross slide mounted on said main slide, means for moving said main tool slide on said turret toward and from the work spindle, a bed for supporting said spindle and said turret, a lever mounted on said bed, and complementary interlocking members on said lever and said cross slide adapted to be alternately engaged and disengaged by the movement of said main slide toward and from said spindle.

7. A metal-working machine comprising a work spindle, a tool slide movable lengthwise toward and from the spindle, a cross slide on the tool slide, mechanism for revolving said tool slide about an axis, mechanism for moving said tool slide lengthwise, mechanism for moving said cross slide, and mechanism for locking said cross slide against individual movement.

8. A metal-working machine comprising a work spindle, a turret adapted to rotate with a step by step movement, a tool slide on the turret, mechanism for advancing and retracting said tool slide, a cross slide on said tool slide, mechanism for feeding and retracting said cross slide, and a lock for locking said cross slide while it is in a retracted position.

9. A metal-working machine comprising a work spindle, a turret adapted to rotate with a step by step movement, a tool slide on the

turret, mechanism for advancing and retracting said tool slide, a cross slide on said tool slide, a lock at the rear end of the travel of the tool slide, a tool-slide-actuating member at the other end of said travel, and means for alternately engaging said cross slide with said lock and said actuating member.

10. A metal-working machine comprising a bed, a work spindle, a turret mounted to rotate on an axis longitudinal of the spindle, a cross slide supported by the turret, and mechanism for automatically moving said cross slide bodily toward and from the end of the work spindle, and mechanism for positively feeding and retracting the cross slide in lines transverse to the axis of the spindle.

11. A metal-working machine comprising a work spindle, a tool slide movable in a path longitudinal of said spindle, a cross slide mounted on said tool slide, a work rest mounted on the tool slide in rear of the cross slide, mechanism for automatically moving the tool slide to position the cross slide and to engage the work rest with the work, and mechanism for feeding and retracting said cross slide relatively to the tool slide and to the work rest thereon.

12. A metal-working machine comprising a work spindle, a tool slide movable in a path longitudinal of said spindle, a cross slide mounted on said tool slide, a work rest mounted on the tool slide in rear of the cross slide and having a rotatable member adapted to enter the open end of a hollow piece of work, mechanism for automatically moving the tool slide to position the cross slide relatively to the work, and to cause said rotatable member to enter the work, and mechanism for automatically feeding and retracting the cross slide relatively to the tool slide and to the work rest thereon.

13. A metal-working machine comprising a bed, a cam shaft thereon having a cam, a lever fulcrumed on said bed in operative relation to said cam, a turret journaled on said bed, a tool slide on said turret, a cross slide on said tool slide, a forming cutter on the cross slide, and mechanism for moving said tool slide to bring the cross slide into operative engagement with said lever, whereupon the actuation of said lever effects the operation of said cross slide and said forming tool.

In testimony whereof I have affixed my signature.

FRANK L. CONE.
